DESIGN FOR A BRACELET CHAIN

John Sand, Newark, N. J., assignor to Gemex
Company, Newark, N. J., a corporation of New
Jersey

Application February 4, 1938, Serial No. 74,875

Term of patent 3½ years

To all whom it may concern:

Be it known that I, John Sand, a citizen of the United States and a resident of Newark, in the county of Essex, State of New Jersey, have invented a new, original, and ornamental Design for a Bracelet Chain, of which the following is a specification, reference being had to the accompanying drawing, forming a part thereof.

In the drawing,

Figure 1 is a plan view of a portion of a bracelet chain showing my new design;

Figure 2 is a side elevational view thereof; and
Figure 3 is a side elevational view of the bracelet shown in Figures 1 and 2, the links of the bracelet, however, being pivoted so as to lie in a single curved plane which conforms to the wrist of the wearer.

I claim:

The ornamental design for a bracelet chain as shown and described.

JOHN SAND.
